US0D1050187S

(12) **United States Design Patent** (10) Patent No.: **US D1,050,187 S**
(45) Date of Patent: ** Nov. 5, 2024

(54) **INTAKE MANIFOLD**

(71) Applicant: **Meihua Ye**, Zhejiang (CN)

(72) Inventor: **Meihua Ye**, Zhejiang (CN)

(73) Assignee: **Yuhuan Ruitong Machinery Factory**,
Zhejiang (CN)

(**) Term: **15 Years**

(21) Appl. No.: **29/955,649**

(22) Filed: **Aug. 2, 2024**

(51) LOC (14) Cl. **15-01**

(52) U.S. Cl. ..... **USPC D15/5**

Primary Examiner — Calvin E Vansant

Assistant Examiner — Cheng Chen

(57) **CLAIM**

The ornamental design for an intake manifold, as shown and described.

DESCRIPTION

FIG. 1 is a front, top perspective view of an intake manifold, showing my new design;

FIG. 2 is a rear, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the intake manifold that form no part of the claimed design.

1 Claim, 8 Drawing Sheets
